CONCEALED HINGE

Joseph Soss, Roselle, N. J.

Application November 9, 1937, Serial No. 173,598

8 Claims. (Cl. 16—148)

This invention relates to what are commonly known as concealed hinges, and particularly to hinges of this class employing butt members with links pivoted to the butt members and to each other to form the concealed linkage, and the object of the invention is to provide a hinge of the class described with means arranged upon at least two of the links employed for forming hoods or housings substantially concealing the linkage of the hinge to form a neat and finished appearance for said hinge; a further object being to provide cover plates or hood members which in addition to concealing the links of the hinge also serves to reinforce and strengthen the hinge linkage; and with these and other objects in view the invention consists in a device of the class and for the purpose specified which is simple in construction, efficient in use, and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a sectional view through a part of a stationary support and swinging member showing one of my improved hinges coupled therewith with the hinge in closed position.

Fig. 2 is a section on the line 2—2 of Fig. 1, showing only the hinge.

Fig. 3 is a view similar to Fig. 2 showing the hinge in an extended position.

Fig. 4 is a view looking in the direction of the arrows 4—4 of Fig. 3, and

Fig. 5 is a perspective view of the hinge in its open position as shown in Fig. 3.

In the accompanying drawing I have shown one method of carrying my invention into effect, and in this illustration two similar butt members 10, 10a are employed. These butt members consist of sheet metal plates stamped and fashioned to form a central U-shaped body 11, 11a having projecting attaching plate portions 12, 12a, by means of which the respective butts may be secured to independent supports 13, 13a as indicated in Fig. 1 of the drawing. For example, the support 13 may consist of a door frame and the support 13a the door or swinging member. The butts 10, 10a are preferably countersunk in adjacent surfaces of the supports 13, 13a as shown, and the spacing between said adjacent surfaces will depend entirely upon the particular installation, it being understood that the said adjacent surfaces may be arranged closer to-

gether by countersinking the hinge butts deeper in said surface.

The top and bottom walls 14, 14a of the respective butts are provided with extensions 15, 15a at one side thereof to form supports for the pintle pins 16, 16a 17, 17a in connection with which long thin links 18, 18a are pivoted, whereas long and wider links 19, 19a are pivoted or mounted on the pintles 17, 17a respectively. The latter links are pivotally coupled with the free end portions of the first named links, that is to say, the link 19 is pivoted to the free end of the link 18a as seen at 20 whereas the free end of the link 19a is pivoted to the end of the link 18 as seen at 20a.

The wide links 19, 19a are also pivoted to each other adjacent the pivots 20, 20a as seen at 21. In the construction shown the links 18, 18a 19, 19a are of laminated construction. The links 18 and 19 are in two groups disposed above and below a single group of the links 18a, 19a as will appear from a consideration of Fig. 4 of the drawing. In other words the links 18 and 19 are arranged side by side as are also the links 18a, 19a.

Arranged upon the links and primarily the links 18, 18a, are cover plates or hood members 22, 22a which have top and bottom walls 23, 23a arranged outwardly of the upper and lower surfaces of the links 18, 18a including part of the links 19, 19a as clearly illustrated in Figs. 1, 4 and 5 of the drawing. One end of each hood member has a curved portion as indicated at 24, 24a which covers and conceals the pivotal coupling between the respective links as at 20, 20a. The pivots 20, 20a extend through the top and bottom walls 23, 23a of the hood portions as do also the pins 16, 16a, the pins 20, 20a projecting beyond the walls 23, 23a. If desired the hood members 22, 22a may be also welded to the links 18, 18a.

Arranged between the pintle pins 16, 17, and 16a, 17a are elongated spacing washers 25, 25a to form on said pins a solid wall structure to reinforce and strengthen the mounting of the links upon said pintles. The washers 25 are arranged between the groups of links 18—18 and the links 19—19 whereas the washers 25a are arranged upon upper and lower surfaces of the links 18a, 19a as will clearly appear upon a consideration of Fig. 4 of the drawing. In other words, the washers 25 are equivalent in thickness to the links 18a, 19a whereas the washers 25a are equal in thickness to the links 18 and 19. It will be understood that solid links may be em-

40

45

50

55

ployed instead of the laminated links in which event solid one-piece spacing members may also be employed. The laminated structure is employed simply to economize the cost of producing 5 the respective parts and to provide for the construction of groups of links of different widths in the production of different sizes of hinges, it being understood that the butts will be modified to suit such changes in sizes.

10 The curved portions 24, 24a of the hoods 22, 22a terminate in straight ends 26, 26a which abut or substantially abut when the hinge is in closed position as is illustrated in Figs. 1 and 2 of the drawing. These straight ends are adapted to fit in 15 the corners 27, 27a of the links 19, 19a when the hinge is in open position so as to form a substantially closed hinge link structure as will be seen upon a consideration of Fig. 5 of the drawing.

With the hinge of the character described it 20 will be apparent that in addition to forming a substantially complete enclosure for the links of the hinge as viewed from the front when the hinge is in open position, the hoods 22, 22a also reinforce and strengthen the complete hinge and 25 render the same dust and dirt proof to a greater degree than would be the case if the links alone were employed as in conventional constructions.

Other washers or shims 25b are employed upon the pins 16, 17, 16a, 17a beyond the upper and 30 lower walls 23, 23a to provide clearance for the protruding ends of the pins 20, 20a. Thin washers 25c are disposed on the pins 17, 17a to make up for the thickness of the top and bottom walls 23, 23a as will be apparent.

35 It will be understood that while I have shown my improved hood construction as applied to a link hinge of predetermined structural arrangement, that my invention is applicable to other types and kinds of hinges in this class, the fundamental principle of the invention residing in 40 the provision of the cover plates or hood members for concealing the joints between the links of a link hinge, especially when in open position. It will appear that the hinge in the accompanying 45 drawing is of the wide throw type such as required in automotive installations, but this feature is not essential to other types of installations and uses of the hinge.

The hood members 22, 22a as will appear, are 50 substantially in the form of channel-shaped plates, one end of which includes the curved portions 24, 24a terminating in the straight ends 26, 26a. It will also be apparent that the top and bottom walls of said hood members cover 55 substantially the entire hinge links or at least the free end portions thereof, when the hinge is in closed position, the two hood parts forming a substantially box-shaped casing in which the links are housed as will appear upon a consideration of Fig. 2 of the drawing.

Having fully described my invention, what I 60 claim as new and desire to secure by Letters Patent is:

1. A hinge comprising butt members, links pivotally coupled to each butt member and to each other for hingedly coupling said butt members, hood members mounted upon and secured to at least one of the links of each butt member forming cover plates concealing substantially all of 65 said link members at the sides thereof adjacent the butt members, each of said hood members including curved portions partially encircling and concealing the pivoted couplings between the respective links, and adjacent ends of said hood 70 members being straight and arranged in juxtaposition

when the hinge is in closed position forming a shield around said pivotal couplings.

2. A hinge comprising butt members, links pivotally coupled to each butt member and to each other for hingedly coupling said butt members, hood members mounted upon and secured to at least one of the links of each butt member forming cover plates concealing substantially all of said link members at the sides thereof adjacent the butt members, each of said hood members including curved portions partially encircling and concealing the pivoted couplings between the respective links, adjacent ends of said hood members being straight and arranged in juxtaposition when the hinge is in closed position forming a shield around said pivotal couplings, and said hood members including top and bottom walls arranged upon upper and lower links of the hinge link unit. 10 15

3. A hinge of the class described comprising substantially similar butt members, two narrow links pivoted one to one butt member and the other to the other of said butt members, two wider links pivoted one to one butt member and the other to the other of said butt members, the free end of the first named links being pivoted to the free ends of the second named links of opposed butt members, said wider links being pivoted together adjacent the last named pivots of said links, and a pair of similar cover plates arranged upon the outer surfaces of the first named links and contacting parts of the second named links to form hood members substantially concealing said narrow links and partially encircling said wide links at the sides thereof adjacent the butt members when said butt members are in open position. 20 25 30 35

4. A hinge of the class described comprising substantially similar butt members, two narrow links pivoted one to one butt member and the other to the other of said butt members, two wider links pivoted one to one butt member and the other to the other of said butt members, the free end of the first named links being pivoted to the free ends of the second named links of opposed butt members, said wider links being pivoted together adjacent the last named pivots of said links, cover plates arranged upon the outer surfaces of the first named links and contacting parts of the second named links to form hood members substantially concealing said narrow links and partially encircling said wide links at the sides thereof adjacent the butt members when said butt members are in open position, and said hood members having curved portions covering the pivotal connections between said narrow links and said opposed wide links. 40 45 50 55

5. A hinge of the class described comprising substantially similar butt members, two narrow links pivoted one to one butt member and the other to the other of said butt members, two wider links pivoted one to one butt member and the other to the other of said butt members, the free end of the first named links being pivoted to the free ends of the second named links of opposed butt members, said wider links being pivoted together adjacent the last named pivots of said links, cover plates arranged upon the outer surfaces of the first named links and contacting parts of the second named links to form hood members substantially concealing said narrow links and partially encircling said wide links at the sides thereof adjacent the butt members when said butt members are in open position, said hood members having curved portions covering the 60 65 70 75 80 85 90 95 98

5 pivotal connections between said narrow links and said opposed wide links, and said hood members including top and bottom walls arranged over said narrow links and said last named pivotal connections.

6. A hinge of the class described comprising substantially similar butt members, two narrow links pivoted one to one butt member and the other to the other of said butt members, two wider links pivoted one to one butt member and the other to the other of said butt members, the free end of the first named links being pivoted to the free ends of the second named links of opposed butt members, said wider links being pivoted together adjacent the last named pivots of said links, cover plates arranged upon the outer surfaces of the first named links and contacting parts of the second named links to form hood members substantially concealing said narrow links and partially encircling said wide links at the sides thereof adjacent the butt members when said butt members are in open position, said hood members having curved portions covering the pivotal connections between said narrow links and said opposed wide links, said hood members including top and bottom walls arranged over said links and said last named pivotal connections, elongated spacing washers arranged between said links on the pivots of said butt members, the external diameter of the pivot portions of said washers corresponding with the external diameter of the pivot portions of said links thereby forming substantially continuous dust-free bear-

ings, and the ends of said hood members adjacent the pivots between the narrow links and the butt members having straight edges arranged in juxtaposition to and paralleling said continuous bearings.

7. The combination with a multiple link concealed hinge of the class described, of a pair of hood members arranged upon and secured to predetermined links of the hinge for covering and concealing substantially all of said links at one side of the hinge when the hinge is in open position and arranged in juxtaposition when the hinge is closed, each of said hood members comprising a substantially box-shaped part open at one side and one end thereof, and the upper and lower walls of each part adjacent the closed end thereof having pivotal apertures.

8. A hinge comprising butt members having offset link receiving portions, a plurality of links pivotally secured to each butt member, one of said links on each butt member being pivotally coupled with each link of the opposed butt member, the other link of each butt member being pivotally coupled to one link only of the opposed butt member, said last named links having a pair of similar cover members mounted on the outer surfaces thereof and disposed between said links and the offset portion of said butt members when the hinge is closed, said cover members forming a box-like hood substantially enveloping all of the links of said hinge at the top, bottom and three sides thereof when the hinge is closed.

JOSEPH SOSS.
